UNITED STATES PATENT OFFICE

MORRIS KORNBLUM, OF BROOKLYN, NEW YORK, ASSIGNOR TO METAL LAMP CORPORATION, OF BROOKLYN, NEW YORK, A CORPORATION OF NEW YORK

DESIGN FOR A LAMP SCREEN

Application filed April 2, 1930. Serial No. 35,122. Term of patent 3½ years.

To all whom it may concern:

Be it known that I, MORRIS KORNBLUM, a citizen of the United States, residing at Brooklyn, in the county of Kings and State of New York, have invented a new, original, and ornamental Design for a Lamp Screen, of which the following is a specification, reference being had to the accompanying drawings, forming part thereof, in which—

Figure 1 is a view in perspective showing my new design; and Fig. 2 is a side elevation.

I claim:

The ornamental design for a lamp screen, as shown.

MORRIS KORNBLUM.
